UNITED STATES PATENT OFFICE

138,382

DESIGN FOR A HOG OILER

Bruce E. Sipe, Kansas City, Mo.

Application January 31, 1944, Serial No. 112,393

Term of patent 14 years

(Cl. D12—2)

To all whom it may concern:

Be it known that I, Bruce E. Sipe, a citizen of the United States of America and a resident of Kansas City, in the county of Jackson and State of Missouri, have invented a new, original, and ornamental Design for Hog Oilers, of which the following is a specification, reference being had to the accompanying drawing, forming a part thereof.

In the drawing:
Figure 1 is a top plan view of a hog oiler, showing my new design.

Figure 2 is an end view of the hog oiler, and
Figure 3 is a side view thereof.

I claim:

The ornamental design for a hog oiler, substantially as shown.

BRUCE E. SIPE.
